LINK CHAIN FOR A BRACELET OR SIMILAR ARTICLE

Ferdinand Armbrust, Warwick, R.I., assignor to Armbrust Chain Company, Providence, R.I., a corporation of Rhode Island

Application May 5, 1958, Serial No. 50,763

Term of patent 14 years

(Cl. D45—4)

Fig. 1

Fig. 3

Fig. 1 is a side elevational view of a link chain for a bracelet or similar article, embodying my new design, the opposite side being the same in appearance;

Fig. 2 is a top plan view, the opposite face being the same in appearance; and

Fig. 3 is an end view of one of the links per se.

I claim:

The ornamental design for a link chain for a bracelet or similar article, substantially as shown and described.
